UNITED STATES PATENT OFFICE

ADOLPHE D. DE CASTRO, OF NEW YORK, N. Y.

INCANDESCENT ELECTRIC LAMP

Application filed July 6, 1929, Serial No. 376,505, and in Poland and Germany September, 1928.

This invention relates to incandescent electric lamps of the kind having two or more filaments and has particular reference to the control of the circuits of such filaments.

5 An object of the present invention is to provide an electric incandescent lamp in which in the event of a filament breaking or burning out, a spare or unused filament in the same lamp becomes automatically and instantaneously incandescent.

According to this invention an electric incandescent lamp, is provided with means controlled by the current adapted to open the contact points carrying current to the upper and lower filaments, causing the lower filament to go out through failure of the thermostat contact point to pass current to the fixed contact point set in the strip or disk of non-conducting material, leaving the upper filament burning steadily and normally, and to close said contact points in the event of the rupture or burning out of the filament that has been burning letting the current pass through the fixed contact point to the lower filament which quickly lights up and continues to burn steadily.

In carrying out the invention according to this mode any type of electric lamp is provided with two filaments having two current-carrying leads and one supporting lead, the latter, merely supporting the two filaments but carrying no current, is sealed off outside the screw base. The lead to the lower filament conducts current between the fixed contact point on the non-conducting strip and the lower filament only and gets into circuit through contact with the contact point on the thermostat element which normally rests on the fixed contact point while its other end, curved, is fixed together with the curved end of the gauge and the free end of the resistance wire of the heating coil or inlay coil, to the strip of non-conducting material.

In the accompanying drawings Figure 1 is a front elevation of the lamp with the device inserted in the base.

Figure 2 is a diagrammatic side elevation of the wiring circuit in the lamp. It shows the wire (1) at its lower base contact (2) its jointure (3) through the strip of non-con-

ducting material (4) in connection with the fixed end of the thermostat (5), the fixed end of the resistance wire (6), of the heating coil or inlay coil (7), on the thermostat element (8) with its contact point (9) resting on the fixed contact point (10) set in the strip of non-conducting material at (11) the bottom of the fixed contact point (12) to which is joined the terminal of the lower lead (13) supporting lower filament (14) fastened to the free lead (15) which extending upward supports the upper filament (16) supported by the main current carrying lead (17) the terminal of which is joined to the free end (18) of the heating coil or inlay coil (7) above which is the gauge (19). The free or cold lead (15) is sealed off outside the base (20).

Figure 3 is a side elevation of the thermostat fastened to a disk.

Upon connecting the lamp in circuit, the current flows through the wire (1) in the base contact (2) to the jointure (3) through the strip of non-conducting material at (4) through the heating coil or inlay coil (7) to the contact points (9-12) direct to leads (13-17) thus lighting both filaments (14-16). The heat generated in the coil or inlay coil (7) causes the thermostat element (8) to lift its contact point (9) from the fixed contact point (12) disconnecting the current from the latter and causing filament (14) to go out leaving filament (16) which, being fed by the current flowing directly from base (2) through wire (1) to the heating coil or inlay coil (7) to lead (17) continues to burn normally and steadily. The rising of the thermostat element (8) is halted by the gauge (19) to facilitate an immediate return of the contact point (9) to the fixed contact point (12). Should the filament (16) break or burn out the thermostat element (8) will at once become de-energized, the contact point (9) will in a few seconds return to its position on top of fixed contact point (12) causing the current to flow into lead (13) instantaneously lighting filament (14) which will continue to burn steadily and normally.

It will be understood that the wire about 100

the thermostat has no function other than to hold the heating inlay in place for the purpose shown and that this wire may be dispensed with altogether. Equally the contact points need not be tungsten but any other material suitable for the purpose. To carry out the idea of normal incandescence and a steadily burning spare filament no heating coil is necessary; and such a device 10 has already been described, set forth and illustrated in an earlier application, filed by your petitioner on June 14, 1926, Serial No. 115,976, and to which this application is a companion application and for which Patent No. 1,758,434 was granted May 13, 1930.

It will be understood that when the lamp of my invention is inserted in the socket the cold thermostat, being in contact with the terminal of the spare filament, the inrush- 20 ing current lights both filaments, the moment the inlay coil gets heated, which takes place in a few seconds, it causes the thermosensitive element to rise from its contact, thus breaking the circuit with the spare filament, leaving one burning steadily and normally. A gauge to control the rise of the thermostat, facilitates the recontact of the thermostat when the filament that is burning breaks or burns out in which case the current 25 finds its way to the spare filament through the cooled thermostat and its contact point.

According to a further alternative the filament circuits may be controlled by elec- 30 tro-magnetic means in place of the thermo- stat device. Thus, for example, a switching 35 device may be employed consisting of a movable hinged or spring element of magnetic material and a fixed contact piece (as shown in 11), a small electro-magnet being suitably 40 disposed to act on the movable element and open the switch when the coil of the said magnet is energized. The magnet coil may be connected in circuit in a similar manner 45 to the heating coil previously described.

It will be understood that the device is not intended to be a means for a flash or flutter light, nor is the object of this improvement in incandescent electric lamps to achieve a retardation of the electric current in the 50 lamp but a stable, steady light, the actual automatic relighting of another filament in the same lamp when the one burning suddenly breaks or burns out.

What I claim is:

In an incandescent lamp, a plurality of filaments, a conductor common to the terminal of each of the filaments, a contact device to maintain a continuous current to both filaments, a thermostat element, including a heating coil, connected with the terminal of one of the said filaments, a gauge secured to said thermostat to control the thermostat element in said lamp, a make-and-break contact device in circuit with the other one of the filaments, said thermo-responsive con-

tact element maintaining a continuous circuit through one of the said filaments and designed to open the make-and-break contact to the other filament.

In testimony whereof I affixed my signature. 70

ADOLPHE D. DE CASTRO.
